APPARATUS FOR CONTINUOUSLY FEEDING A BAND OF TEXTILE OR SIMILAR MATERIAL

Joannes Andreas Kuypers, Weert, Netherlands

Application June 24, 1955, Serial No. 517,888

Claims priority, application Netherlands June 28, 1954

2 Claims. (Cl. 203—150)

The invention refers to a method for continuously cutting and winding a band of textile or similar material, from the roll of material, and to a machine applying this method.

By applying such a method it would be possible to cut a straight band of material by means of a number of cutters into straight strips, if for practical operation this method did not present certain serious difficulties. In the first place the width of the strips can hardly be altered; in the second place the strips are cut off at fixed lengths, while thirdly it is practically infeasible to cut off the outer strips in the same and right width throughout, which causes much waste.

To obviate the said drawbacks the method according to the invention is characterized in that a double band of flatly rolled material is unwound from a roll rotating round a shaft perpendicular to the unwinding shaft, on to a drum mounted in a line with the first shaft, and revolving at the same speed of rotation; on the admission-side of the drum an admission-cone spreads out the band of material like a tube, which is then pulled by a constant, yet adjustable tractive force over a cylindrical part of the rotating drum, while at the periphery of the stretched tube-shaped material a rotating cutter cuts off a spiral strip, which is under tension wound on a revolving roll.

The machine in which the method according to the invention is applied, is characterized in that it is provided with a frame in which two shafts, are fitted in a line, revolving at the same speed of rotation, when in operation; one of these shafts carries a roll with the double flatly rolled tube-spaced band of material, the unwinding shaft of which is perpendicular to the revolving shaft; on the other rotating shaft is mounted the unwinding drum provided with an admission-cone, and a cylindrical part, the periphery of this latter part being fitted with a number of fixed bolts on the outside covered with card clothing; between every two bolts is fitted a reciprocating rod, likewise covered on the outside with card clothing; a spring presses the rolling end of the rod against an inclined panel with an adjustable angle of gradient. The machine is on one side provided with a guide for lifting a strip of material cut off by the rotating cutter; behind the cutter is fitted a driven winding-roll on to which the cut-off strip is wound under tension.

The machine according to the invention is further characterized in that the panel on which the ends of the spring-loaded-reciprocating rods covered with card clothing are pressed, can be adjusted revolving as it is round a shaft perpendicular to the direction of the axis of rotation of the machine; an adjustable screw-rod is at a certain distance from the adjusting-shaft connected with the panel by means of a joint.

The machine according to the invention is, moreover, characterized in that the cut-off strip passed between two toothed wheels, and is wound on a winding-roll with a driving-shaft rotating at a slightly greater speed than that of the unwinding cut-off strip; the said wheels are

2

connected with this shaft by means of a friction-coupling.

Below follows a detailed description of a band-cutting machine applying the method according to the invention as shown in the diagram,

Figure 1 is a side-view of the complete machine;

Figure 2 is a section along the line II—II of Figure 1;

Figure 3 is a detail-drawing of a reciprocating rod covered with card clothing.

On the frame 1 are mounted in a line the shaft 2 in the bearings 4 and 5, and the shaft 3 in the bearings 6 and 7. Both shafts are driven at the same speed of rotation, and consequently synchronize when in operation.

According to the illustrated example the two shafts 2 and 3 are driven by one and the same electromotor, 8, which is provided with a rope-pulley 9, while the shaft 2 is fitted with the rope-pulley 10, which is connected with the rope-pulley 9 by means of a rope. For driving, the shaft 3 an intermediate shaft has been mounted in the bearings 15 and 16. The transmission of effort from the shaft 2 to the shaft 3 is effected by the chain-gears 12, 13, 14, and 17, 18 and 19. This means of transmission is only given by way of illustration; it is clear, that any other suitable way will have the same effect.

Perpendicular to the shaft 3 is fitted a shaft-stump 21 on which the unwinding-roll 20 revolves. A band of material is wound on this roll 20, woven in tube-shape, so that it lies flat and double on the roll. During the cutting process according to the invention this flat tube-spaced band 37 is gradually unwound from the roll 20.

A fixed or adjustable drum 22 is fitted by means of a cotter on the shaft 2 in line with the shaft 3; the double band of material is pulled over this drum as a taut tube, whereafter at the periphery a spiral strip is cut off in a way to be described below. The drum 22 has an admission-cone 23, which spreads out the oncoming double band of material 38 into a tube. Behind this conical part 23 is the cylindrical part 24, serving mainly to pull the stretched tube-shaped material gradually backwards throughout its periphery, hence away from the roll 20.

This gradual passage of the tube-shaped material is effected as follows:

The outside periphery of the cylindrical part 24 of the drum is at equal distances provided with a number of bolts 25, fixed by the nuts 26. These bolts 25 are partly covered on the outside with card clothing 27. A reciprocating rod 28 is fitted between each pair of fixed bolts 25; a detailed description of this rod and its operation, as shown in Figure 3, follows below.

The bar of the rod, which may have a round, square or rectangular section, runs through the passage 50 of the back plate 49 of the drum 22. This rod is likewise covered on the outside with card clothing 45. This card clothing consists of a foundation of hard felt or a similar material, filled with a great number of metal pins 46 with bent heads. These pins are fixed vertically in the felt, while the heads 47 of the pins are all bent in the same direction. When the rods 28 move backwards and forwards along the axis in a direction opposite to the pin-heads 47, the pins will glide over the material with a reverse movement of the rods 28, however, the pin-heads 47 will grip into the material pulling it backwards. It is obvious, that when the rods 28 move towards the unwinding-roll 20, the stretched tube-shaped material is held by the pin-heads of the card clothing 27 of the fixed bolts 25, which face the same direction as the pin-heads 47 preventing the taut tube-shaped material from recoiling, while the reciprocating rods 28 gradually and

smoothly pull the tube-shaped material away from the unwinding-roll 20.

The reciprocating movement of the rods 28 is effected by the tension of a draw-spring 51 fastened to a hook 53 on the rod 28, and a fixed hook 52 fitted on the inlet-plate 49. The free end of the rod 28 is provided with a roller or ball 30, which is held on the rod by a screw-case 48. With its roller-end the rod presses on the inclined panel 31 revolving round the shaft 32. The angle of gradient of the panel 31 is adjustable by means of a rod 34, which is connected in 33 with the panel 31 by means of a joint, and provided at the other end with a screw 35, so that by turning the wheel 36 the rod 34 can be turned inward or outward. When the machine is in rotation the ends 30 of all the rods 28 are in permanent contact with the inclined panel 31. When moving upwards on the panel 31, the rods 28 will with the turned-back pin-heads 47 pull the tube-shaped material 38 gradually backwards, while in the downward movement of the rods 28 the pin-heads will glide over the material. The material cannot recoil, as in this action the pins 27 of the rotating bolts 25 hold the material in place.

The extension 57 of the frame 1 carries a second electromotor 42, whose shaft is at one end fitted with the rotating cutter 41, while its other end drives a rope through the rope-pulley 45, which drives the winding-gear of the cut-off strip.

The tube-shaped material 38 stretched over the drum 22 is on one side slightly lifted by a sector-shaped guide 39, to free the material from the cylinder-casing. This guide 39 is provided with a slot through which the round cutter 41 passes when cutting off the material. The cut-off strip 58 then passes between two toothed wheels 54 and 55 with opposite rotation, eventually to be wound on the winding-roll 56. The two toothed wheels 54 and 55, and the winding-roll 56 are driven by the motor 42 or by the drum 22, at a speed of rotation that is slightly greater than the unwinding speed of the cut-off strip 58 at the cutter. These toothed wheels and the winding-roll 56 are preferably connected with their respective driving-shafts by means of a friction-coupling, that the cut-off strip may well be kept tight throughout.

The method according to the invention, and the machine applying it have the great advantage that while continuously cutting off a strip of material, the width of such a strip can be regulated by merely changing the angle of gradient of the panel 31. If the position of the panel 31 is perpendicular to the direction of the revolving shafts 2-3, the width is 0, as the rod 28 stands still, and the material 38 does not move; the greatest width will be obtained at a maximum angle of gradient of the panel 31.

As the speed of the spiral of the cut-off strip is but low, this does not hinder the operational application of the band.

I claim:

1. A feeding means for a band cutting mechanism for

continuously cutting a spiral band of material from a fabric tube, comprising a mandrel mounted for rotation about a fixed axis, a drum mounted coaxially on said mandrel for rotation therewith, an annular series of 5 relatively spaced retainer cards fixedly supported on said drum, a further annular series of relatively spaced feeding cards mounted on said drum for reciprocal movement axially of drum and mandrel between adjoining retainer cards, said feeding cards and said retainer cards both 10 having outwardly presented similarly axially inclining carding teeth for operative engagement with the interior of a tube of fabric received on said mandrel, an axially inclined flat cam element and means supporting same in axial alignment with said drum, and cam follower 15 members extending axially from said respective feeding cards into operative engagement with said cam element, whereby rotation of the said drum will cause reciprocatory feeding movements of said feeding cards, said cam element being mounted for angular adjustment about an 20 axis transverse to the axis of said drum to vary the effective feeding strokes of said feeding cards simultaneously and uniformly, the flat face of said cam element being parallel to said transverse axis.

2. A feeding means for a band cutting mechanism for 25 continuously cutting a spiral band of material from a fabric tube, comprising a mandrel mounted for rotation about a fixed axis, a drum mounted coaxially on said mandrel for rotation therewith, an annular series of relatively spaced retainer cards fixedly supported on said 30 drum, a further annular series of relatively spaced feeding cards mounted on said drum for reciprocal movement axially of drum and mandrel between adjoining retainer cards, said feeding cards and said retainer cards both having outwardly presented similarly axially inclining carding teeth for operative engagement with the interior of a tube of fabric received on said mandrel, an axially inclined flat cam element and means supporting same in axial alignment with said drum, and cam follower members extending axially from said respective 35 feeding cards into operative engagement with said cam element, whereby rotation of the said drum will cause reciprocatory feeding movements of said feeding cards, said cam element comprising a flat cam plate, means supporting said plate adjacent one axial end of the mandrel for angular adjustment about an axis normal to and transecting the rotational axis of the mandrel, and means operatively connected to said cam plate for angularly adjusting said cam plate.
